(57) **CLAIM**

The ornamental design for an enteral feeding pump cassette connector, as shown and described.

DESCRIPTION

FIG. 1 shows a perspective view of a enteral feeding pump cassette connector made in accordance with the design of the present invention;

FIG. 2 shows a bottom perspective view of the enteral feeding pump cassette connector of FIG. 1;

FIG. 3 shows a top view of the enteral feeding pump cassette connector of FIG. 1;

FIG. 4 shows a right side view of the enteral feeding pump cassette connector of FIG. 1;

FIG. 5 shows a left side view of the enteral feeding pump cassette connector of FIG. 1;

FIG. 6 shows an end view of the enteral feeding pump cassette connector of FIG. 1; and,

FIG. 7 shows an opposing end of the enteral feeding pump cassette connector of FIG. 1.

The broken line showing is for illustrative purposes only and forms no part of the claimed design.
